[57] CLAIM

The ornamental design for a hair accessory display, as shown.

DESCRIPTION

FIG. 1 is a top, front and left side perspective view of a hair accessory display showing my new design, the broken-line disclosure of a hair accessory being for illustrative purposes only and forming no part of the claimed design;

FIG. 2 is a reduced front elevational view thereof;

FIG. 3 is a reduced left side elevational view thereof, the right side being a mirror image of that shown;

FIG. 4 is a reduced top plan view thereof, the bottom being a mirror image of that shown;

FIG. 6 is a fragmentary top, front, and left side perspective view of a third embodiment thereof, the only difference residing in the configuration of the support pegs, with the bottom being shown broken-away for convenience of illustration; and,
